UNITED STATES PATENT OFFICE.

EDWARD H. WILLIAMS, OF SOUTH BEND, INDIANA, ASSIGNOR TO PERKINS CORPORATION, OF MISHAWAKA, INDIANA, A CORPORATION OF INDIANA.

STOCK-WATERING TANK.

1,391,150.

Specification of Letters Patent. Patented Sept. 20, 1921.

Application filed April 1, 1921. Serial No. 457,685.

To all whom it may concern:

Be it known that I, EDWARD H. WILLIAMS, a citizen of the United States, residing at South Bend, in the county of St. Joseph and 5 State of Indiana, have invented certain new and useful Improvements in Stock-Watering Tanks, of which the following is a specification.

The invention relates to stock watering 10 tanks, and has for its object to provide a device of this character wherein the water may be heated in cold weather for preventing freezing of the same. Also to provide a stock watering tank having a heater therein 15 whereby the maximum heating of the water may be attained with the least consumption of fuel and the water maintained above the freezing point for a long time.

A further object is to provide a stock 20 watering tank comprising a receptacle, said receptacle having disposed therein a heater which heater is formed by a casing substantially semi-circular in cross section and extending through an opening in the front wall 25 of the receptacle, said heater being spaced from the bottom of the receptacle and from the rear wall thereof and provided with a smoke stack extending upwardly from the rear end of the casing and spaced from the 30 rear wall thereof and forming means for additionally heating the water within the tank.

A further object is to provide a vertically 35 movable door having a damper therein, said door forming means for closing the outer end of the heater casing.

With the above and other objects in view 40 the invention resides in the combination and arrangement of parts as hereinafter set forth, shown in the drawings, described and claimed, it being understood that changes in the precise embodiment of the invention 45 may be made within the scope of what is claimed without departing from the spirit of the invention.

In the drawings:

Figure 1 is a perspective view of the watering tank.

Fig. 2 is a vertical transverse sectional 50 view through the watering tank.

Referring to the drawings, the numeral 1 designates the elongated body of a watering tank, and 2 an outwardly extending horizontally disposed flange to which is secured 55 a bottom 3. Disposed within the body 1 is a casing 4, which casing is substantially

semi-circular in cross section and has its flat side 5 downwardly disposed and spaced from the bottom 3 of the tank, so that water will entirely surround the casing 4 and be 60 in contact with its upper and lower walls, thereby obtaining a maximum heating surface for heating the water when a fire is built within the fire box 6.

The forward end of the casing 4 extends 65 through an opening 7 in the front wall 8 of the body 1 and is provided with a flange 9, which flange is secured to the front wall 8 by means of rivets 10 thereby securely fastening the front wall 8 to the casing 4. 70

The rear end of the casing 4 is provided with a flange 11, and to which flange is secured by means of rivets 12 an upwardly extending stack 13, to which stack products of combustion from the fire box 6 pass, and as said products of combustion pass through 75 the stack 13 the heat radiated by the stack is also utilized for heating the water, thereby obtaining the maximum heating of the water with the least consumption of fuel. 80 Stack 13 is spaced from the rear wall of the tank thereby allowing water to entirely surround the stack for heating purposes. It will be seen that the flange 11 forms supporting means for the rear end of the casing 85 4 thereby relieving any strain that might be placed on the flange 9 and its securing rivets. The stack 13 extends through a bracket 14 adjacent the upper edge of the rear wall of the body 1 and braces the stack 90 and at the same time forms an additional brace for the casing 4 as a whole.

Secured to the front wall 8 adjacent the sides of the fire box opening are vertically disposed angular guide members 15, in which 95 guide members a door 16 is vertically movable. The door 16 forms a closure for the fire box 6 and is provided with a conventional form of damper 17, by means of which damper the draft through the fire box and 100 stack 13 may be controlled and regulated.

From the above it will be seen that a heated stock watering tank is provided which is simple in construction and one wherein water may be easily heated and maintained at 105 a temperature above the freezing point for a long period of time with a relatively small consumption of fuel.

The invention having been set forth what is claimed as new and useful is:

The combination with a stock watering tank having a horizontally disposed bottom,

of a heater therefor, said heater comprising a horizontally disposed casing forming a fire box, said casing being semi-circular in vertical transverse cross section and having 5 its flat side in parallel relation to the bottom of the tank and spaced therefrom, the forward end of said casing extending through the front wall of the tank and secured there-
to, the rear end of said casing terminating 10 in a marginal flange disposed in a vertical plane, the lower side of said flange form-

ing means for spacing the rear end of the casing from the bottom of the tank, a vertically disposed stack carried by the rear end of the heater and spaced from the rear wall 15 of the tank, said stack being provided with a flange at its lower end, said flange being secured to the flange at the rear end of the horizontally disposed casing.

In testimony whereof I affix my signature. 20

EDWARD H. WILLIAMS.
